ATTY:

UNITED STATES PATENT OFFICE

2,051,260

RADIO RECEIVING ANTENNA CIRCUIT

Laurence J. Lesh, Chicago, Ill., assignor to Associated Electric Laboratories, Inc., Chicago, Ill., a corporation of Delaware

Application June 18, 1934, Serial No. 731,025

4 Claims. (Cl. 250—20)

My invention relates in general to improved radio receiving antenna circuits, and more specifically to an improved circuit arrangement and interconnection of radio receiving antenna the 5 object of which is to improve the selectivity thereof and to neutralize or reject interfering waves and prevent them from interfering with the wanted signals.

In order to attain this object I have shown as 10 an example one circuit arrangement having various devices shown in proper relationship and adjustable to meet various conditions. In general the arrangement shown consists of a plurality of antenna branches, connected together at 15 a common point. One branch has the radio receiving set coupled thereto in the usual manner, while the other branches include suitable variables of resistance, capacity and inductance with ground shunts therefrom through variable 20 resistances. The arrangement shown may be utilized to neutralize or reject interfering waves from various sources and I have shown the method of neutralizing interference emanating from a telephone line by substituting a telephone 25 circuit for one of the antenna branches. It will be understood that interference may arise from various causes such as electrical machinery, power lines and such interference may arise from devices located at various points relative to the 30 radio circuit. Therefore I have shown certain connecting switches in the drawing for cutting out or switching certain of the elements in order to meet the requirements of a particular instance. In other words, for certain interfering 35 waves it may be found necessary to disconnect certain or all of the ground shunts while in other instances it will be found preferable to close such shunts.

In the accompanying drawing consisting of a 40 single figure I have shown three branched antenna circuits converging at a common point designated at X. The antenna branch A' includes a suitable coupling L' L⁴ to the radio receiving set RR, this coupling and also the radio 45 receiving set may be of any commonly used type although I prefer a coupling of the inductive type to an ungrounded receiving set. The branch antenna A² has in series therewith a resonant circuit including inductance L², capacity C² and 50 resistance R¹, adjustable to the received frequency. This resonant circuit is connected to ground through a variable resistance R⁵ and a disconnecting switch SW². In addition branch A² is connected to the arm of switch SW¹ through 55 which this branch may be connected to the an-

tenna A⁴ or to a telephone line TL. When switched to the telephone line it is connected thereto through a phase shifter comprising variable resistances R² and R³ and a three plate shunt condenser C⁴. The line TL is, of course, 5 bridged by the usual substation instrument circuit including talking and listening instrumentalities as indicated at T. In use the telephone line when connected to this circuit acts as one of the antenna branches and is substituted for branch A⁴. Branch antenna A³ has in series therewith another resonant circuit comprising either a variable resistance R⁴ and a variable capacity C³ or the variable inductance L³ with the capacity C³ dependent on the position of a switch SW³. In addition to the resonant circuit this antenna branch A³ also has a shunt to ground through a disconnecting switch SW⁴ and a variable resistance R⁶.

The variable shunt resistances involved should 20 be variable from 0 to 1,000,000 ohms non-inductive resistance, while the inductances capacities and resistances in the resonant circuits will be chosen in values appropriate to the frequency of the received radio signals and such values are 25 well known to those conversant to the art.

It is desirable to have the antenna branches of the same effective electrical length and to have these branches arranged symmetrically in the same plane although the physical arrangement 30 admits of wide variation. It is also desirable to have variable coupling between the inductances L² and L³ in the two resonant circuits.

By a proper selection and adjustment of the 35 various components of this arrangement it has been found possible to effectively neutralize or eliminate from the radio receiving set the interference emanating from a nearby source, of a magnitude comparable with the incoming radio waves. This neutralization permits clear 40 and undisturbed reception of a desired radio signal under conditions where reception by a simple radio antenna is impossible. It has been found possible to completely balance out the beat or heterodyne note produced by an oscillator 45 in the vicinity of the radio receiver against an incoming radio carrier wave, under conditions where conventional set-ups would render reception impossible. It has also been found that proper adjustments of the components of 50 my improved antenna system will also demonstrate useful directive sensitivity and sensibility.

It will be understood that in practice the selection and adjustments of the antenna components is determined by tests to meet the con- 55

ditions imposed by local conditions such as the disposition of the antenna branches relative to each other, to surrounding objects, such as walls, and to ground.

- 5 As an example, in one instance, it was necessary to eliminate interference in a radio set occasioned by the presence of a complicated electrical machine in the same building, where it was impractical to remove the interference at the 10 source by the customary method of enclosing the machine in a grounded metal shield, and applying interference suppression to the sparking devices causing the interference.

In this instance, space limitation dictated that 15 the antenna arms A⁴ and A² of my arrangement be not longer than ten feet and that they be placed almost parallel and about two feet apart. Under these conditions it was found by experiment that the best results were obtained by closing switch SW¹ to branch A⁴, closing switch SW² 20 so that a shunt to ground of about 100,000 ohms resistance was obtained, closing switch SW³ to connect up inductance L³, and closing switch SW⁴ and adjusting resistance R⁶ to minimize resistance or direct to ground. The variable components were then adjusted until interference was 25 eliminated and satisfactory radio reception was provided at the desired wave length.

Having described the general arrangement and 30 features of my invention, what I consider to be novel and desire to have protected by Letters Patent will be pointed out in the appended claims.

What is claimed is:

1. A radio receiving antenna system comprising 35 a plurality of antenna branches connected together at a common point, a radio receiver coupled to one branch, a telephone circuit included in another branch together with means

for controlling the resonance and phase thereof at radio frequency, and phase and resonance control means included in a third one of said branches.

2. In a radio receiving antenna system, a plurality of antenna branches radiating from a common point, a radio receiving set coupled to one branch between the antenna and the common point, a resonant circuit included in each of the other branches having variable components adjustable to change the characteristics thereof, and means for providing ground shunts of varying resistance to the other branches, said components and shunts adjustable to eliminate interference in the receiving set due to oscillations 15 from an interfering source.

3. In a radio receiving antenna system, a plurality of antennas, a circuit connecting one antenna to a common point, a radio receiving set coupled to said circuit between the antenna and the common point, a circuit connecting each of the other antennas to the common point, a resonant circuit in each of said other circuits between the respective antennas and the common point, and circuits for connecting each of said other antennas to ground through a variable resistance independent of said resonant circuits.

4. In a radio receiving antenna system, a pair of antenna branches connected together at a common point, each branch connected to the common point through a resonant circuit having means for controlling the resonance and phase thereof, a telephone circuit also connected to said common point through a similar resonance circuit, a variable ground shunt for said telephone circuit, and a radio receiving set coupled to one of said branches.
